PRESTON C. STEPHENSON, OF SIOUX CITY, IOWA, ASSIGNOR OF TWO-SIXTHS TO HARRY GURSHTEL AND ONE-SIXTH TO E. E. BARON, BOTH OF SIOUX CITY, IOWA

BUSHING-REMOVING TOOL

Application filed November 10, 1928. Serial No. 318,420.

My invention relates to bushing removing tools of the type adapted to remove bushings from any device with which bushings are used.

3 An object of my invention is to provide a tool of this character which is capable of pulling the bushing or of drifting the bushing from its hub.

4 A further object is to provide such a bushing puller which is capable of securing such a secure grip on the interior of a bushing as to render it impossible for the grip to be loosened during drifting or pulling operations.

5 More specifically, my invention embodies a bushing tool of the type provided with a threaded jaw member adapted to be threaded into a bushing and provides in addition to the threaded jaw means for 10 tightening the engagement of the threads of the jaw with the bushing after the tool has been threaded into the bushing.

With these and other objects in view, my 15 invention consists in the construction, arrangement and combination of the various parts of my device, whereby the objects contemplated are attained, as hereinafter more fully set forth, pointed out in my claims, and illustrated in the accompanying drawings, in which:

Fig. 1 is a side view of the bushing remover in engagement with the bushing of a pulley.

Fig. 2 is a sectional view through the 20 pulling bolt.

Fig. 3 is a view of a somewhat modified form of the stem.

Fig. 4 is a view of one end of the bushing remover.

40 Fig. 5 is a view of the other end of the bushing remover.

Bushing removers of the type employing a threaded pulling bolt adapted to be threaded into a bushing to secure a grip on the bushing, together with means for drifting or applying pressure to the pulling bolt so as to remove the bushing, are not new. It is not my intention to claim broadly such a device. However, there are objections to 45 this type of bushing remover, chief among

which is the fact that quite often during the drifting operation, the pounding will weaken the threaded connection between the bolt and the bushing, the bolt often rotating under the vibration of the drifting until finally the bolt will be entirely driven from the bushing.

55 My invention remedies this objection by providing means for applying outward pressure to the threads of the bolt to securely lock the threads in engagement with the bushing after the bolt has been threaded in place. The bushing of an ordinary pulley 8 is indicated in the drawings by the reference character 9. This bushing is ordinarily of bronze or Babbitt or some metal 60 which is soft enough to be cut readily by steel.

65 The pulling bolt is indicated generally by the reference character A and comprises a sleeve 10 and a nose 11. The nose 11 is split as at 12 to form several sections or jaw members, as indicated in Fig. 4 and is 70 exteriorly threaded as at 13.

75 The nose is tapered as shown in the drawings so as to be easily inserted in a bushing.

80 The threads 13 are of the type having one side substantially perpendicular to the axis of the bolt and the other side inclined from the base of an adjacent thread to form a sharp edge 14. In other words, the threads are V shaped in cross section with one perpendicular face.

85 The edges 14, where they are intersected by the slots 12, form cutting teeth or points 15.

90 The slots 12 serve the double purpose of forming the cutting teeth and also of allowing the jaw members to be spread apart.

95 The sleeve 10 of the bolt is exteriorly threaded at 16 and interiorly threaded at 17. The upper end of the sleeve is formed with a squared or polyhedral head 18, to which a wrench may be applied for rotating the bolt as a unit.

100 For spreading the jaw members 11, I provide a conical wedge 19 and a threaded stem 20, threaded into the threads 17 of the sleeve 10 and provided with a squared or

polyhedral head 21, adapted to receive a wrench to receive rotation therefrom.

The wedge 19 and stem 20 may be either formed integrally as shown in Fig. 3 or as 5 separate elements, as shown in Fig. 2.

In using the tool, the tapered nose 11 is inserted into a bushing as far as it will go and then rotation is given to the bolt through the medium of the squared head 18, pressure being applied to urge the nose into the bushing. When the nose has 10 acquired a grip on the bushing, it will pull itself into the threads it has started and will thread its way into the bushing, cutting the 15 threads with the sharp cutting teeth 15.

After the nose has been threaded to a sufficient depth in the bushing, a wrench is applied to the head 21 and the stem 20 threaded into the sleeve 10, forcing the 20 wedge 19 to expand the jaw members of the nose 11.

This expansion produces two results: In the first place, the threads 13 will be forced outwardly against the threads which have 25 been formed in the bushing, obtaining a very secure frictional grip on the bushing. In the second place, the points or teeth 15 will be forced into the bushing sufficiently so that it will be very difficult to rotate the 30 bolt in the bushing after the locking has been effected.

The bolt may now be driven out by a drift pin and hammer or may be pulled by means of a pulling device, shown in Fig. 1. 35 This comprises a yoke 22, having the legs 23 to engage on either side of the hub of the pulley or to engage against a device in which the bushing is located and a collar 24, through which the bolt A is loosely received. 40

The wing nut 25 is threaded upon the threads 16 of the bolt A and serves to exert pulling pressure against the bolt to draw it through the collar 24. The pressure against 45 the collar 24 is transmitted to the pulley through the medium of the arms 23 and the counter-pulling pressure is transmitted directly to the bushing through the bolt. Thus the bushing may be pulled from 50 the pulley by rotating the wing nut 25.

The grip of the jaws against the bushing effectively prevents the rotation of the bolt relative to the bushing during the pulling or drifting operation and the frictional engagement of the threads with the bushing securely holds the bushing against any possibility of loosening of the jaws.

Some changes may be made in the construction and arrangement of the parts of 60 my invention without departing from the real spirit and purpose of my invention, and it is my intention to cover by my claims, any modified forms of structure or use of mechanical equivalents, which may 65 be reasonably included within their scope.

I claim as my invention:

1. In a bushing remover, a pulling bolt, having an internally threaded bore, a tapered hollow nose formed on the end of said bolt, and divided radially to form three 70 separable jaws, a wedge positioned within said hollow nose, adapted to expand the jaws, a threaded stem, threaded into the threaded bore, adapted to be rotated to transmit longitudinal pressure to the wedge, 75 said bolt being externally threaded, a wing nut threaded thereon, and a yoke including a collar loosely receiving said bolt, said yoke being adapted to be engaged by the wing nut, and, in turn, to engage a device in 80 which a bushing is located.

2. In a bushing remover, a pulling bolt, provided with means for receiving rotative pressure, and having an internally threaded bore, a tapered hollow nose formed on the 85 end of said bolt, and divided radially to form three separable jaws, a wedge positioned within said hollow nose, adapted to expand the jaws, a threaded stem, threaded into the threaded bore, adapted to be rotated to transmit longitudinal pressure to the wedge, 90 said bolt being externally threaded, a wing nut threaded thereon, and a yoke including a collar loosely receiving said bolt, said yoke being adapted to be engaged by the wing nut, and, in turn, to engage a device in 95 which a bushing is located.

3. In a bushing remover, a pulling bolt, having an internally threaded bore, a tapered hollow nose formed on the end of said bolt, and divided radially to form a plurality of separable jaws, a wedge positioned within said hollow nose, adapted to expand the jaws, a threaded stem, threaded into the threaded bore, adapted to be rotated to transmit longitudinal pressure to the wedge, 100 said bolt being externally threaded, a wing nut threaded thereon, and a yoke including a collar loosely receiving said bolt, and of substantial depth so as to secure the bolt against lateral tilting movement, said yoke being adapted to be engaged by the wing nut, and, in turn, to engage a device in 105 which a bushing is located.

4. In a bushing remover, a pulling bolt, having an internally threaded bore, a tapered hollow nose formed on the end of said bolt, and divided radially to form a plurality of separable jaws, a wedge positioned within said hollow nose, adapted to expand the jaws, a threaded stem, threaded into the threaded bore, adapted to be rotated to transmit longitudinal pressure to the wedge, 110 said bolt being externally threaded, a wing nut threaded thereon, and a yoke including a collar loosely receiving said bolt, said yoke being adapted to be engaged by the wing nut, and, in turn, to engage a device in 115 which a bushing is located, said yoke in 120

cluding a pair of arms opposed to each other on opposite sides of the axis of the bolt.

5. In a bushing remover, a pulling bolt, having an integrally threaded bore, a tapered hollow nose formed on the end of said bolt, and divided radially to form three separable jaws, a wedge positioned within said hollow nose, adapted to expand the jaws, and a threaded stem, threaded into the 10 threaded bore, provided with means to receive a wrench from which to receive rotative pressure, said tapered, hollow nose being exteriorly threaded with a thread, V-shaped in cross section, having a face which 15 is substantially perpendicular to the axis of the bolt and which faces toward the body of the bolt.

6. In a bushing remover, a pulling bolt having an internally threaded bore, a tapered, hollow nose formed on the end of said bolt and divided radially to form a plurality of separable jaws, a wedge positioned within said hollow nose, adapted to expand the jaws, a threaded stem threaded into the 20 threaded bore, adapted to be rotated to transmit longitudinal pressure to the wedge, said bolt being externally threaded, a wing nut having an integral arm projecting a substantial distance laterally from the bolt, 25 said yoke including a pair of spaced arms positioned on opposite sides of the axis of the bolt and including a collar of substantial depth loosely receiving said bolt and supporting it against lateral tilting movement, said yoke being adapted to be engaged by the wing nut and in turn to engage a device in which a bushing is located.

Signed this 26th day of October, 1928,
in the county of Woodbury and State of
40 Iowa.
